UNITED STATES PATENT OFFICE.

SAMUEL BROWN, OF EASTHAMPTON, MASSACHUSETTS, ASSIGNOR TO NASHAWANNUCK MFG. CO., OF EASTHAMPTON, MASSACHUSETTS, A CORPORATION.

MAN'S SUSPENDERS.

No. 904,176.

Specification of Letters Patent.

Patented Nov. 17, 1908.

Application filed April 6, 1908. Serial No. 425,464.

To all whom it may concern:

Be it known that I, SAMUEL BROWN, a citizen of the United States, residing at Easthampton, in the county of Hampshire and 5 State of Massachusetts, have invented a new and useful Improvement in Men's Suspenders; and I do hereby declare the following when taken in connection with the accompanying drawings and the letters of reference marked thereon, to be a full, clear, and 10 exact description of the same, and which said drawings constitute part of this specification, and represent, in—

Figure 1 a view in elevation of a pair of 15 suspenders constructed in accordance with my invention. Fig. 2 a sectional view through one of the back ends on the line *a—b* of Fig. 1.

This invention relates to an improvement 20 in men's suspenders.

Heretofore the elastic and non-elastic webbing used in the manufacture of men's suspenders has been given an ornamental character either by printing designs upon it after 25 the manner of printing fabrics, or by weaving it in looms of the Jacquard type which produce upon its surface ornamental patterns formed by over-shot threads. Of these two methods of ornamentation that by printing fails of its purpose because the effect is 30 cheap, while the method of weaving in Jacquard looms is so expensive as to be prohibitory in all but the highest class of goods.

The object of my present invention is to 35 utilize plain webbing in the production at a low cost of very richly ornamented suspenders without injury even to those portions of the webbing made elastic by the introduction of strands of india rubber.

With these ends in view my invention consists in a pair of men's suspenders comprising 40 two shoulder straps, front suspender ends connected with the front ends of the said

shoulder-straps, and narrower than the same, and elastic rear suspender ends connected 45 with the rear ends of the said straps, all of the webbing, elastic and non-elastic, entering into the suspenders having its outer face ornamented by embossing producing raised and depressed surfaces. 50

In carrying out my invention the non-elastic shoulder straps 2, the narrow non-elastic front suspender ends 3 and the elastic rear suspender ends 4 of the suspenders are formed from plain suspender webbing which by sub- 55jection to heat and pressure between engraved rolls is provided upon its outer face with an ornamental, embossed pattern whereby at a small cost and without any injury to the elastic or non-elastic portions of the web- 60bing the suspenders are greatly enriched in appearance. I say without injury to the elastic or non-elastic portions of the webbing be- 65cause contrary to expectation I have discov- ered that elastic webbing may be subjected to heat and pressure without any apparent deterioration in its elastic quality.

I claim:—

As a new article of manufacture, a webbing having elastic and non-elastic strands 70 entering into the webbing and having its outer face ornamented by embossing producing raised and depressed surfaces, whereby plain webbing may be utilized in the produc- 75tion of richly ornamented suspenders without injury to those portions of the webbing made elastic by the introduction of strands of india rubber.

In testimony whereof, I have signed this specification in the presence of two subscri- 80bing witnesses.

SAMUEL BROWN.
